TENSION DEVICE

Leonard C. Marsac, Cranford, N. J., assignor to
 The Singer Manufacturing Company, Elizabeth,
 N. J., a corporation of New Jersey

Application August 9, 1946, Serial No. 689,430

15 Claims. (Cl. 242—150)

1

This invention relates to sewing machines and more particularly to an improved thread tension device installed in the bracket-arm head of a family type sewing machine.

Mechanisms for tensioning the needle thread of sewing machines are known in the art. However, previously used tension devices, that have been generally accepted by the trade, have been positioned mainly exteriorly of the sewing machine head. It is a primary object of the present invention to provide an improved thread tensioning device, a major portion of which is received within an aperture provided in the head of a family type sewing machine. In other words, it is an object of the invention to provide a compact tension device that has a minimum protuberance from the head of the machine.

Another object of the invention is to provide a generally improved thread tension device for use with sewing machines.

Still another object of the invention is to provide a thread tension device having a simple means for accurately adjusting the degree of tension imposed upon the needle thread.

Other important objects of the invention will be apparent from the following detailed description and appended claims.

The invention consists in the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 is a side elevational view of a portion of a sewing machine bracket-arm fitted with a tension device embodying the invention;

Fig. 2 is an end elevational view of the bracket-arm and tension device shown in Fig. 1;

Fig. 3 is a sectional view taken on the line 3—3 of Fig. 1 and looking in the direction of the arrows;

Fig. 4 is a top plan view of the tension device, a portion of the bracket-arm being shown in section;

Fig. 5 is a sectional view taken substantially on the line 5—5 of Fig. 3 and looking in the direction of the arrows; and

Fig. 6 is an exploded perspective view of the tension device.

In the preferred embodiment of the invention illustrated in the drawings, numeral 11 indicates an overhanging bracket-arm of a family type sewing machine. The arm terminates in a head 12 that supports the usual reciprocating needle

2

bar 13, thread take-up 14, presser-bar 16, and presser-bar lifter 17. A V-shaped tension-releasing lever 18, having arms 19 and 21, is pivotally supported in the head 12 by a screw 22. The arm 19 is operated by the presser-bar lifter 17 when the lifter approaches fully raised position. The arm 21, which is biased counterclockwise by a beehive spring 24, is provided with a boss 26, the purpose of which will hereinafter appear.

10 The head 12 also supports a tension device 27, a major portion of which is received within an aperture 28 (Figs. 3 and 4) formed in the head 12. The rear portion of the tension device is disposed in a cylindrical hole 29 forming a reduced extension of the aperture 28 through the inner wall 15 of the head 12.

The tension device comprises a plate 31 having a cylindrical aperture into which is fitted the front end of a support member that is in the form of a hollow cylindrical or tubular barrel 32.

20 An annular lip 33 (Fig. 3), on the front end of the barrel 32 is spun over the edge of the hole in the plate 31 and, thereby, securely holds the plate against the front face of a shoulder 34 formed on the barrel 32. The plate 31 is adjustably held to

25 the head 12 by a screw 36 which passes through a slotted countersunk hole 37 and then enters a threaded hole 38 in the head 12. The plate 31 has an inclined tongue 39 and check spring stop lug 41 extending from opposite sides thereof.

30 The tongue 39 in combination with the front surface of the plate 31 acts, during the operation of threading the sewing machine, to guide a thread between the proximate flattened median portions of a pair of dished tension disks 42 and

35 43. The disks are centrally apertured and thereby fit over the exterior surface of a hollow, cylindrical, reduced-diameter neck 44 formed integral with and extending concentrically from the front end of the barrel 32. The disk 42 enters

40 a countersunk recess 46 formed in the front of the plate 31, thus insuring that a thread will always be guided between the disks 42 and 43 and not behind the disk 42. The rear end of the barrel 32, that enters the hole 29, is diametrically slotted as at 47 and thereby provides a

45 pair of longitudinal slits for accommodating opposed diametrical lugs 48 formed on the external circumference of an internally threaded and externally shouldered abutment nut 49. A biasing means, in the form of a coiled compression spring 51, fits into the hollow barrel 32 and biases the nut 49 in a direction rearwardly of the plate 31. A hollow cylindrical sleeve 52, having an annular ring 53 formed integral therewith and

55 an end 54 (Fig. 3) of reduced internal diameter,

fits over the external surface of the barrel 32. This sleeve is held to the barrel 32 in any desired position by a set screw 56, and the end 54 acts as a retainer for the spring pressed nut 49. One end 57 of a conventional lightweight check spring 58 is anchored by entering a small hole 59 provided in the front face of the ring 53. The tension of the check spring 58 can be adjusted by loosening the set screw 56 and rotating the sleeve 52. The main body of the check spring surrounds the front end of the sleeve 52 and the collar 34 (Fig. 3). The front end of the spring is bent to form a thread-engaging loop 60 and a circular end portion 61 which encircles the neck 44 in front of the plate 31 and the disks 42 and 43. A guard plate 62 has a backwardly extending arm 63, a thread-guiding hook 64, an index mark 65, a partly cutaway annular rim 66, three backwardly extending lugs 67, a forwardly extending stop lug 68, and a central aperture by which the plate slips over the neck 44 in a position directly in front of the disk 43. The cutaway rim 66 provides clearance for the loop-end arm of the check-spring 58, which loop-end 61 surrounds the neck 44 of the barrel 32 and is housed in the guard-plate 62 in a manner to prevent entanglement of the needle thread. From Fig. 5, it can be seen that the lugs 67, bent inwardly as they are from the flat wall portion of the plate 62, do not interfere with movement of the thread loop 60 and act as spacing members for the plate 62. When the tension device 27 is installed on the head of a sewing machine, the arm 63 enters a hole 70 provided in the head 12, whereby the guard-plate 62 is restrained against turning movement. A numerically engraved dished washer 69 having a central aperture and a rearwardly extending lug 71 slips over the neck 44 in a position directly in front of the guard plate 31. The face of the washer 69 is provided with a plurality of holes 72, the purpose of which will presently appear.

When the tension device 27 is installed in a sewing machine, the tension imposed upon the sewing machine thread may be adjusted by turning a screw 73, which has a steep-pitched external thread 74, and a longitudinally extending diametrical slot 75. The stem of the screw 73 is formed with a reduced diameter portion 77, an increased diameter portion 78 journaled in the neck 44, and an adjusting knob head 79, the latter having a roughened ring to provide a finger grip. When the device 27 is assembled, part of the stem of the screw 73 is located within the barrel 32 and the threaded end of the stem enters a steep-pitch threaded hole in the nut 49. The head of the screw 73 and a portion of the stem are positioned exteriorly of the aperture 28, and a pin 81, projecting from the rear face of the head 79, selectively enters any one of the holes 72 in the washer 69.

The tension device is assembled in the following manner. First the disks 42 and 43 are slipped over the neck 44 with the flattened surfaces of the disks adjacent one another. Then the main body of the check spring 58 is slipped over the barrel 32 and the loop end 61 is placed over the neck 44 in front of the two disks previously placed thereon. Then the compression spring 51 is placed in the hollow portion of the barrel 32 and the nut 49 is placed behind the spring 51 with the lugs 48 engaging the slots 67. Thereafter the sleeve 52 is slipped over the barrel 32, care being taken to enter the end 57 of the spring 58 in the hole 59. By tightening

the set screw 56 sufficiently, the sleeve is held in place. Following this, the guard plate 62 and dial washer 69 are slipped onto the neck 44, and the stem 76—77—78 of the screw 73 is inserted through the neck 44 and the barrel 32 until the threads 74 engage the threads in the nut 49. Turning the screw 73 clockwise causes the nut 49 to move outwardly against the spring 51 and thus forces the pin 81 on the screw head 79 into engagement with one of the holes 72 in the washer 69. This causes the washer 69 to turn clockwise until its lug 71 engages the lug 68 on the guard plate 62. Continued turning of the screw 73 causes the plate 62 to turn clockwise until the arm 63 encounters the plate 31. When this occurs, the numeral 9 on the dial washer 69 becomes colinear with the index mark 65 on the plate 62. Further turning of the screw 73 can be accomplished by pulling on the head 79, thereby releasing the pin 81 from the hole 72 and further compressing the spring 51. Continued turning of the screw 73, while pulling out on the head 79, results in the pin 81 again engaging one of the holes 72 thus preventing further clockwise turning of the screw. In this condition of adjustment, the spring 51 is fully compressed and the spring 51 biases the head 79, the washer 69, the guard plate 62 and the two washers 63 and 42 against the plate 31. The flattened faces of the disks 42 and 43 are thereby held together with the maximum available force thus providing the maximum thread tension regulating force for which the device is designed. In this condition, the tension device may be attached to the sewing machine head by insertion of the barrel 32, the sleeve 52 and the other parts located to the rear of the plate 31 into the recess 26 and the hole 29. At the same time the arm 63 will enter the hole 70 in a known manner. A reducing thread-tension adjustment can be effected by turning head 79 in a counter-clockwise direction. This relaxes the spring 51 and moves the washer 69 to various positions wherein the numerals 8, 7, 6 etc, consecutively become colinear with the index mark 65 on the arm 63.

When the tension device 27 is in position in the head 12, the threaded end 74 of the screw 73 projects into the cavity of the sewing machine head and is engaged by the boss 26 (Fig. 2) of the arm 21. Thus when the lifter 17 is raised to its fully raised position, the boss 26 pushes the screw 73 forward a sufficient amount to release the thread controlling action of the disks 42 and 43.

The disks 42 and 43 can be cleaned without removing the whole tension device from the sewing machine. In order to accomplish this it is simply necessary to remove the screw 73 by turning it counterclockwise, and at the same time pulling on the head 79 to disengage the pin 81 from the holes 72. When the screw has been removed, the washer 69, guard-plate 62 and loop end 61 can be removed to permit removal of the disks 42 and 43.

Having thus set forth the nature of the invention, what I claim herein is:

1. A tension device for sewing machines comprising a hollow support member, a compression spring located within said support member, a spring compressing member slidably mounted in said hollow support member, retainer means for limiting movement in one direction of said spring compressing member in said support member, a lightweight spring surrounding a portion of said

retainer means a pair of thread tensioning disks carried on a front portion of said support member, and an adjusting means located partly in front of said disks and partly within said support member.

2. A tension device for sewing machines comprising a plate, a hollow cylindrical barrel extending from said plate rearwardly thereof, a check spring surrounding said barrel, a sleeve adjustably secured to said barrel and having a hole for anchoring one end of said check spring, a compression spring positioned within said barrel, a nut slidably mounted within said barrel and biased rearwardly by said compression spring, a neck formed on the forward end of said barrel, a plurality of thread tensioning disks carried by said neck, and a screw threaded into said nut and arranged to press said disks together and against said plate.

3. A tension device for sewing machines comprising a plate, a hollow cylindrical barrel secured to said plate and extending rearwardly thereof, a compression spring within said barrel, a threaded nut engaging one end of said spring, a pair of tensioning disks positioned in front of said plate, and an adjusting screw having a head in front of said disks and a threaded stem adjustably screwed into said nut.

4. A tension device for sewing machines comprising a hollow support member, a biasing means within said support member, a bias compressing member slidably positioned within said support member, a pair of thread-tensioning disks carried on said support member and located entirely in front of said biasing means, and an adjusting member located partly in front of said disks and partly within said support.

5. A tension device for sewing machines comprising a hollow cylindrical barrel, a compression spring within said barrel, a threaded nut engaging said spring and slidably positioned within said barrel, a pair of tensioning disks carried on the front end of said barrel, and an adjusting screw having a head in front of said disks and a threaded stem screwed into said nut.

6. A tension device for sewing machines, comprising, a hollow cylindrical supporting member, opposed tension-disks mounted upon a forward portion of said supporting member, a tension-disk compressing spring housed in a rearward portion of said supporting member, and means including an adjusting screw extending through said supporting member for varying the tension-disk compressing force of said spring.

7. A thread-tension device for sewing machines, comprising, a tubular supporting member, a plate rigidly carried by said supporting member intermediate the ends thereof, a pair of opposed tension-disks mounted on said supporting member at one side of said plate, a tension-disk compressing spring housed in said supporting member at the opposite side of said plate, and means including an adjusting screw extending into said supporting member from the tension-disk side of said plate to the compression spring side thereof for changing the effective pressure of said spring.

8. A thread-tension device for sewing machines comprising, a tubular supporting member, a plate rigidly carried by said supporting member intermediate the ends thereof, and a check-spring carried by said supporting member, said spring having one end wrapped around said support at one side of said plate and the other end

wrapped around said support at the other side of said plate.

9. A thread-tension device for sewing machines comprising, a tubular supporting member, a plate rigidly carried by said supporting member intermediate the ends thereof, a check spring carried by said support member, said spring having one end wrapped around said support at one side of said plate and the other end wrapped around said support at the other side of said plate, and a check spring stop lug carried by said plate.

10. A thread-tension device for sewing machines comprising, a tubular supporting member, a plate rigidly carried by said supporting member intermediate the ends thereof, a pair of opposed tension-disks mounted on said supporting member at one side of said plate, a tension disk compressing spring housed in said supporting member at the opposite side of said plate, and a check-spring surrounding said supporting member at the compression spring side of said plate and terminating at one end in a loop embracing said supporting member at the side of said tension-disks remote from said plate.

11. A tension device for sewing machines comprising a hollow cylindrical barrel, a check spring surrounding said barrel, a sleeve adjustably secured to said barrel and having a means for anchoring one end of said check spring, a compression spring positioned within said barrel, a nut slidably mounted though held from turning within said barrel and biased rearwardly by said compression spring, a neck formed on the forward end of said barrel, a plurality of thread tension disks carried by said neck, and a screw threaded into said nut and arranged to press said disks together in a direction toward said barrel.

12. A tension device for sewing machines comprising a hollow cylindrical barrel, a pair of tensioning disks carried by the front end of said barrel, a disk-biasing compression spring carried in the back end of said barrel, a check spring having a coiled portion which surrounds the back end of said barrel and a loop which surrounds the front end of said barrel, a guard plate positioned in front of said check spring loop, and radially inwardly bent ears on said guard plate, said ears providing clearance for said check spring loop.

13. A tension device for sewing machines comprising a hollow cylindrical barrel, a pair of tension disks carried on the front of said barrel, a disk-biasing compression spring carried on the back end of said barrel, a check spring having a coiled portion which surrounds the back end of said barrel and a loop which surrounds the front end of said barrel, and an anchoring means for one end of the check-spring adjustable relative to said hollow cylindrical barrel.

14. A thread-tension device for sewing machines comprising, a hollow support member, a mounting means rigidly secured to said support member between the ends thereof, a pair of tension disks mounted on said support member in front of said mounting means, a guarding means having a plurality of spacing members and at least one forwardly extending member, said guarding means being mounted on said support member in front of said tension disks, an indicating means having a backwardly extending member for engaging said forwardly extending member on said guarding means, a compression spring housed in said support member at the op-

posite side of said mounting means from said tension disks, a spring compressing member located in said support member behind said compression spring, an adjusting screw having a head for engaging said indicating means, said adjusting screw having a stem that enters said hollow support member and engages said spring compressing member, and separable engaging means for securing said adjusting screw to said indicating means for turning movement therewith.

15. A thread-tension device for sewing machines, comprising, a tubular support member, a plate rigidly carried by said supporting member intermediate its ends, a pair of opposed tension-disks mounted on said supporting member in front of said plate, a guard plate having a plurality of backwardly extending lugs and a single forwardly extending lug mounted on said supporting member in front of said tension disks, a dial washer having a backwardly extending lug mounted on said supporting member in front of said guard plate, said dial washer being provided with a plurality of equally spaced holes in the face thereof, a tension disk compression spring

5 housed in said support member at the opposite side of said plate from said tension disks, a threaded nut housed in said supporting member behind said compression spring, and an adjusting screw having a head carrying a pin located in front of said dial washer and having a stem that passes through said tubular support member and is screwed into said threaded nut.
